UNITED STATES PATENT OFFICE

HERMANN PETSCH, OF RECKLINGHAUSEN, GERMANY

COKE OVEN

Application filed July 7, 1924, Serial No. 724,708, and in Germany August 1, 1923.

This invention relates to coke ovens and more particularly to improvements in the type of oven described in British Patent No. 23,459 of 1910, in which the walls or binders 5 of the heating flues were provided with air passages adapted to conduct the air necessary to support combustion to the heating flues.

In coke ovens, as heretofore constructed, and which were provided with vertical heating flues, an extremely high temperature was produced at the point where the heating gases were burned, particularly in cases where the air for combustion was highly preheated. In fact, so high was this temperature that frequently the refractory bricks, of which the walls of the flues were made, were fused, this fusing occurring usually toward the end of the coking process when the coke body had absorbed practically its full capacity of heat 20 and the refractory bricks could transmit no more heat thereto.

In the structure shown in the British patent mentioned an attempt was made to overcome this difficulty and, in fact such difficulty was, 25 to a large extent, overcome, but I have found in practice, for the purpose of obtaining a uniform heat throughout the length of the flue, it is essential to proportion along the flue the amounts of air for combustion, i.e., to supply the total air in several different portions in a manner which is accomplished by the special structural means hereinafter claimed.

It is therefore the object of this invention 35 to provide a special method of proportioning the amounts of air admitted to the heating flues at various levels whereby gradual combustion and uniform heating throughout the length of each heating flue is obtained instead of having a maximum temperature at one point and from there a decrease of such temperature toward the exit end of the flue.

Specifically stated the invention consists 45 in proportioning the amounts of air supplied by dimensioning the air outlets in such manner that their cross sectional areas are gradually increased from the initial point of combustion toward the exit of the flue whereby a substantially uniform temperature may be 50 maintained throughout the length of the flue.

Further objects and advantages which are gained by this invention will appear as the following specific description is read in connection with the accompanying drawings which form a part of this application and in 55 which:

Figure 1 is a detail longitudinal vertical sectional view of a part of the heating wall of a coke oven showing my improvement, the section being taken on the line 1—1 of Fig. 2; 60

Figure 2 is a transverse sectional view taken on the line 2—2 of Figure 1;

Figure 3 is a section view similar to Figure 1 showing a modification, and taken on the line 3—3 of Fig. 4; 65

Figure 4 is a section view similar to Figure 2 and taken on the line 4—4 of Figure 3.

Referring more particular to Figures 1 and 2 of the drawing, *m* indicates the oven chamber, of which there may be any number, as 70 will be readily understood. Between the several oven chambers usually employed to make an oven block, is arranged a plurality of heating flues *a* separated by transversely extending walls *b*. These heating flues are connected, as is shown in all of the figures, with the gas main *g* by vertically disposed nozzles *f* which serve to conduct the required amount of gas from the distributing main *g* to the base of each flue *a*. 75

As shown in Figure 1, each wall or binder *b* is provided with a vertical passage *k* communicating at its lower end by means of a diagonal conduit *i* with a distributing passage or main *h* arranged to receive air from 85 any suitable source. This air may be, if desired, preheated in the recuperators or regenerators (not shown). The main passages *k* terminate in the present example slightly above a point midway of the height of the 90 walls and each has a plurality of outlets indicated at *c*, *d* and *e*, which gradually increase in size. In other words, the outlet *c* which, as shown, is situated at the lowest level, is the smallest, *d* is the next larger and 95 *e*, which is situated at the highest level, is the largest of the three air ports. This manner of graduating the outlets *c h d e* is an important feature of my invention and the essential means for obtaining the required 100

proper proportioning of air for supporting combustion. It is, of course, to be understood that the graduating of the air outlets as shown and described may be varied somewhat without in any way departing from the spirit of this invention.

In Figure 1 and Figure 3 the outlets *c*, *d* and *e* extend from the passages *k* to opposite sides of the wall or binder *b* and on diverging lines, but if desired, this arrangement may be changed, and other positions and locations of the discharge openings *c*, *d* and *e* may be adapted. Normally it is found desirable in the construction shown in Figure 1 to provide two air discharge-openings at each level in the same flue, these openings to be situated oppositely to each other.

One variation of the above described form is disclosed in Figure 3 wherein each of the walls *b*¹ and *b*³ are provided with the air supply passages *k* and the discharge orifices *c*, *d* and *e*, as shown in Figure 1. Each alternate wall *b*²—*b*⁴ are provided with passages *t* which extend throughout the length of these walls and communicate at the base thereof with conduits or flues *u*. The flues *t* in this instance are utilized for conducting away the waste products of combustion from the main collecting channel *s*, and the conduits *u* have communication directly with the chimney. In the form of Figure 1 the waste products of combustion pass from the flues *a* directly into the collecting channel *s* which is coupled to, or communicates with the chimney at a suitable point not shown.

In the construction shown in Figs. 1 and 2 the passages *k* are supplied with air through diagonally arranged conduits *i* which communicate with the air main *h* arranged beneath the coke chamber *m*. In Figs. 3 and 4 the conduits *i* are connected with the main *h'* and the conduits *u* are connected to the discharge main *h*² which communicates with the chimney. Both mains *h'* and *h*² as shown, are arranged beneath the coke chamber *m* and occupy the space occupied by the main *h* in the construction of Figures 1 and 2.

In the operation of the construction disclosed in Figures 1 and 2, combustible gas, for instance, purified coke oven gas, returned from the by-product plant is conveyed to the distributing channel or main *g* from whence it passes into the heating flues *a* by way of the nozzles *f*. At the same time air, preferably which has been preheated in the regenerators or recuperators, is conveyed to the main *h*, from whence it passes through the conduits *i* into the passages *k* and is discharged therefrom through the graduated openings *c*, *d* and *e* into the flues *a* from opposite sides thereof.

The products of combustion rise in the heating flues *a* and pass outwardly into the collecting channel *s*, where they are taken off

to the chimney in the direction of the arrows in Figure 1.

The operation of the structure shown in Figures 3 and 4 is identical with that of Figures 1 and 2 except that after the products of combustion have been discharged from the upper end of the heating flues *a* into the collecting channel *s*, they then pass downwardly through the channels *t* in the alternate walls or binders and are discharged through the passages *u* into the discharge main *h*² from which they are conducted to the chimney. In this form, however, it will be noted that there is only one discharge of air into each flue at each level, as distinguished from the two opposite jets at each level disclosed in Figure 1. However, the correct proportioning of the air outlets with this type by the proper dimensioning of the air produces the same effect and results as to uniform heating as are obtained with the symmetrical arrangement of opposite openings as disclosed in Figures 1 and 2.

The proportioning of the amounts of air fed to the flues at the respective levels which will be obtained by dimensioning the air outlets *c*, *d* and *e* according to my invention as described above enables me to achieve with certainty a gradual combustion of the heating gas. This ensures to perfectly distribute the heat of the products of combustion over the whole length of the heating flues and to obtain a uniform and even temperature throughout the height of the heating wall.

The foregoing facts have been determined in practice by taking pyrometrical readings at various levels in the heating flues which disclose only very slight difference in temperature between the hottest and coolest points. This uniform temperature effectively obviates any overheating and consequently prevents fusion of the refractory material and at the same time assures complete heating without causing carbon or graphite deposits in the flues. The success of this progressive combustion and uniform heating displays itself in operation by a very considerably reduced coking time without putting any unusual burden upon the refractory material. It has also been found out in practice that there is a considerable increase in the yield of coke and by-products and the coke produced is of uniform size with considerable better physical properties.

In consequence of the uniform and even heating which obviates any excess of heat expense, I have found that less gas is consumed in obtaining the required amount of heat and that the production of tar, ammonia and benzol is materially enhanced both as to quality and quantity.

When by-product ovens were first built the height of the oven chambers was about 6 feet only, but the tendency for some time past has been to increase the height so as to

increase the output of each individual oven, and at the present time many ovens are being built as high as 11 feet and more. In these high ovens it has been found almost impossible to obtain correct coking throughout, but by properly proportioning the admission of air as described I have found that an oven constructed in accordance with the present invention may be of maximum height without in any way impairing uniform coking throughout.

What I claim is:—

1. In a coke oven, vertical flues defined by walls, certain of which are provided with vertical air passages having outlets at different levels discharging into the flues, the cross sectional areas of said outlets increasing from the base of the flue toward the upper end thereof, and means for feeding gas to the base of the flues.
2. In a coke oven, vertical walls defining vertical heating flues, means for feeding gas to the base of the flues, certain of said walls adjacent to each flue, having vertical air passages therein with outlets discharging into the flues, said outlets being arranged at different levels and graduated so that their cross sectional areas increase from the gas inlet end to the upper end of the flues.
3. In a coke oven, vertical walls defining vertical heating flues, means for feeding gas to the base of said flues, certain of said walls adjacent to each flue, having vertical air passages therein, beginning from below the base of the flue and being provided with outlets discharging into the flues at different levels, said outlets being graduated so that their cross sectional areas increase from the lowermost to the uppermost.
4. In a coke oven, vertical walls defining vertical heating flues, means for feeding gas to the base of said flues, certain of said walls having vertical air passages therein, with outlets arranged at different levels and discharging into the flues and oppositely to each other, the cross sectional areas of said outlets progressively increasing from the gas inlet end to the upper end of the flues.
5. In a coke oven, vertical walls defining vertical heating flues, means for feeding gas to the base of the flues, certain of said walls having vertical air passages therein, a common horizontal air main below the flues and having connection with said vertical air passages, said air passages provided with outlets arranged at different levels and discharging into the flues and oppositely to each other, the cross sectional areas of said outlets progressively increasing from the gas inlet end to the upper end of the flues.

6. In a coke oven, walls defining vertical heating flues, means for feeding gas to the base of said flues, two of said walls on opposite sides of one of said flues having vertical air passages therein with outlets which are

arranged at different levels and oppositely to each other and communicating with said one of said flues, the cross sectional areas of the said outlets progressively increasing from the gas inlet end to the upper end of the flues.

7. In a coke oven, walls defining vertical heating flues, means for feeding gas to the base of said flues, two of said walls on opposite sides of one of said flues having vertical air passages therein which communicate below with a common horizontal air-main and are provided with outlets arranged at different levels and oppositely to each other and communicating with said one of said flues, the cross sectional areas of the said outlets progressively increasing from the gas inlet end to the upper end of the flues.

8. In a coke oven, a vertical combustion flue defined by walls, one of said walls being provided with an air passage having port means at different levels discharging into said flue and constituting means for supplying air for combustion to said flue, the port means at one of said levels above the lowermost level being adapted to convey air therethrough at a volume rate greater than that of the port means at the lowermost level when subjected to substantially the same pressure, together with means for feeding gas to said flue adjacent the base thereof.

9. In a coke oven, a vertical combustion flue defined by walls, one of said walls being provided with an air passage having port means at different levels discharging into said flue and constituting means for supplying air for combustion to said flue, the port means at any one of said levels above the lowermost level being adapted to convey air therethrough at a volume rate greater than that of the port means at any lower level when subjected to substantially the same pressure, together with means for feeding gas to said flue adjacent the base thereof.

In testimony whereof I affix my signature.

HERMANN PETSCH.
